(57) **CLAIM**

The ornamental design for a hors d'oeuvre skewer, as shown and described.

DESCRIPTION

FIG. 1 is a perspective view of the hors d'oeuvre skewer.
FIG. 2 is an enlarged bottom plan view of the hors d'oeuvre skewer.

FIG. 3 is an enlarged top plan view thereof.

FIG. 4 is a left side elevational view thereof.

FIG. 5 is a right side elevational view thereof.

FIG. 6 is a front elevational view thereof.

FIG. 7 is a rear elevational view thereof; and,

FIG. 8 is an alternate perspective view thereof shown with environment.

The broken lines showing in FIG. 8 are for the purposes of illustrating the environment of the article only and form no part of the claimed design.
